A. Kindermann.

3821

PATENTED JAN 25 1870
Design for Wreath.

United States Patent Office.

A. KINDERMANN, OF CLEVELAND, OHIO.

Design No. 3,821, dated January 25, 1870.

DESIGN FOR A WRENCH.

The Schedule referred to in these Letters Patent and making part of the same.

To all whom it may concern:

Be it known that I, A. KINDERMANN, of Cleveland, in the county of Cuyahoga, and State of Ohio, have invented a new and improved Design for Wrench, of which the following is a full, clear, and exact description.

The figure is a sectional plan.

My design consists of a shield shaped head, *a*, from one angle of which projects a spur, *b*, the head loosely enclosing a shank, *c*, having one straight side, coincident with the straight side of the head *a*, and having at the other side three salients, *d e h*, whereof one, *e*, is a rounded head and neck, and the other two are of similar symmetrical shape reversed, one at each side of the projection *e*.

A spur, *i*, similar in all respects to the spur *b*, projects from the shank *c*, opposite to and parallel with the other spur.

The adjacent faces of the spurs have transverse projections *k k* and *l l*, opposite and similar, and transverse grooves *m m* in each face, between the projections *k* and *l*.

The design also includes a handle, *A*, one end of which is enclosed in the head *a*, such end being recessed at *n*, in a manner correspondent to and for the reception of the salient *e*.

Having thus described my invention, What I claim as new, and desire to secure by Letters Patent, is—

The design for a wrench, as described and shown.
A. KINDERMANN.
